TIME DELAYED SWITCH

Lewis J. Reynolds, Houston, Tex., assignor, by mesne assignments, to William E. Ford, Houston, Tex.

Application October 8, 1953, Serial No. 384,842

5 Claims. (Cl. 200—122)

This invention relates to a time delayed switch, and more particularly to an improved electric current flow cutoff device which, when located in an electric circuit, enables the circuit to remain closed for a limited time interval following switch actuation to a circuit opening position.

An object of the invention is to provide a simplified structure which will be economical to manufacture and reliable in operation and which in use will maintain a closed circuit in current flow relation for a predetermined time after a circuit opening manipulation has been made. By way of example, a household installation would have a wall switch in a room lighting circuit, and when the room is to be darkened the switch is moved to an off position but the light will continue room illumination for a few minutes, during which a person could leave the lighted room or could see his way to lie down in bed and possibly be asleep before the room is in darkness. Various time settings and uses can be employed.

A further object of the invention is to provide a delayed action cutoff making use of a thermally expansible liquid whose volume is controlled to make and thereafter break a circuit through the application and removal of heat to the liquid, with the opening of the circuit occurring upon temperature and volume reduction.

More specifically the invention deals with a circuit containing a heater to raise the temperature of a column of mercury or similar fluid and thereby expand the same to maintain a pair of contacts closed, there being an arrangement operable at will to render the heater ineffective, whereupon the temperature of the mercury returns to normal, with a resultant volume contraction to open the current flow path between the contacts after a predetermined delay dependent upon the cooling off period.

The invention will be better understood upon reference to the accompanying drawing, wherein Figs. 1 and 2 are circuit diagrams illustrating mercury switch embodiments in one of which the switch and heater are in parallel circuit and in the other of which the switch and heater are in series circuit.

Referring first to Fig. 1, the mercury switch is illustrated as including a closed container or capsule 1 having opposite enlargements or bulbs 2 and 3 connected by a narrow central neck portion of small diameter to contain a body of mercury or other fluid 4 which when at normal temperature is contained primarily in the lower bulb 2 at a low level within the central neck portion. When heat is applied to the mercury, the column will rise beyond the narrow neck and into the expansion space provided by the uppermost bulb 3. For convenience the mercury container 1 may be formed of glass, and it has projected through and fused and sealed in opposite end walls a pair of contacts or electrodes 5 and 6 which end in spaced apart relation to one another so as to be bridged by the current conducting mercury when expanded. When the mercury bridge has given up its heat, its level will fall to re-establish the gap between the spaced electrodes or contacts 5 and 6. As shown in Fig. 1, the

2

lower contact is fully submerged in the liquid at all times, and the upper contact 6 is submerged only when the liquid level rises above the lower height of the contact. This arrangement can be variously modified; as, for example, the two electrodes may be arranged side by side or projected laterally into the container with both terminating entirely above the contracted liquid level.

An electrically energized heater element or resistance wire 7 is located in close proximity with the body of mercury, and preferably is replaceably mounted at the center of the lowermost bulb 2. If desired, this heater coil can be in the nature of a small light bulb whose filament will supply ample heat as well as a light signal to indicate when current is flowing therethrough.

Suitable conductor wires join the heater 7 and the mercury switch in parallel relation to one another, and each in series with a current responsive indicator as a light bulb 8. Other types of electrically energized units may be used in place of the light bulb 8 if the switch is to be employed for other than controlling a lighting circuit. Circuits through both the heater and the mercury switch are controlled as by means of a multiple way switch and the usual conductor wires, and a simplified illustration of the multiple switch includes a pivotal means as a swingable blade 9 for selective movement between several positions. In the full line position shown, the blade 9 engages a contact 10 whose conductor leads to the electrode 5, and this may be referred to as the delayed off position. In the broken line position of the blade, indicating that the blade has been swung to the right, in Fig. 1, a contact 11 will receive current for flow to the heater 7, and this position may be referred to as the on position. An optional instantaneous off position of the blade is indicated by dotted lines with the blade swung toward the left in Fig. 1.

In the full line relation of the parts shown, no current is supplied to the light bulb 8. As soon as the blade 9 is swung into engagement with the contact 11, the lamp will be instantaneously lighted and current flowing through the heater 7 will raise the temperature of the mercury body 4 and raise its level for submerging both the electrodes 5 and 6. Thereafter, if the switch blade 9 is swung to the instantaneous off position, the supply of current is immediately cut off and the light bulb 8 is extinguished. On the other hand, if the switch blade 9 is returned for engagement with the contact 10, current flow through the heater is cut off but current flow then continues through the expansible body and the electrodes 5 and 6 for continuously supplying current for constant illumination of the lamp 8 so long as the temperature of the fluid body 4 keeps the volume at a level at which the electrodes are bridged. When the temperature finally drops to sufficiently contract the liquid and thereby break the path of current flow between the electrodes, the lamp 8 will be extinguished.

In the embodiment shown in Fig. 2, current responsive indicator as the lamp 12 is in series with a heater 13 and with spaced apart electrodes or contacts 14 and 15 mounted at the top and the bottom, respectively, of a mercury containing capsule 16. The capsule itself is pivoted at its lower end on a pin 17, and the mercury contained therein when cooled has a contracted volume to bring its level slightly below the position of the contact 14 when the container 16 is in an erect or vertical position, indicated by full lines in Fig. 2. In this relation the electric circuit is open, and when it is desired to close the circuit the container 16 is tilted to one side so that the mercury level rises above or is in contact with the contact 14 to provide a path of current flow between the contacts 14 and 15 and through the heater 13 and lamp 12. The heater is positioned closely adjacent the container when the container is tilted to its limit of

full-on position, and supplies heat for a temperature and volume increase of the mercury so that when the container is tilted back to the full line vertical position the heated volume of liquid is then at a level above the contact 14 for continuing the submergence thereof for a time interval necessary for contraction of the liquid. The distance between the heater and the container in its erect full line position is sufficient to remove the container from the influence or field of heat application. Any number of intermediate positions of the container may be provided, and two intermediate positions are indicated by broken lines, both of which position the container at distances from the heater which enable the heater to be at least partially effective and to an extent which retards the rate of liquid cooling off. In this fashion the contraction of the liquid at different rates affords a selection of time delay interval for the cutoff of current flow. By proper selection of the volume of mercury and the location of the electrode 14 an instantaneous cutoff of current flow can be had in the vertical full line position of the container 16 if the hot volume places the liquid level just below the contact 14.

For holding the pivoted container 16 in any of its desired positions of adjustment, a bar 18 has one end pivotally mounted at 19 with its intermediate portion extending along an arc defined by the free swinging end of the container 16 so as to engage the same. This arcuate portion of the bar 18 is provided with a series of retaining notches any one of which can receive the free end of the container and locate it in any position of adjustment. At its free end the link 18 is joined to one end of a tension spring 20 whose opposite end is suitably anchored in fixed relation with the pivot 17. This spring force affords a yielding resistance to displacement of the link 18 about its pivot for insuring retention of the switch container in any position to which it may be adjusted.

The invention as specifically described is subject to various modifications, such as come within the scope of the appended claims.

What is claimed is:

1. In a time delay electric switch for an electric circuit including a current responsive indicator, a container for thermally expansible liquid, means mounting said container for movement between on and off positions of said switch, a pair of electrodes carried by the container and projected into the container on position, an electric heater in series with the electrodes and positioned adjacent the on container position for the application of heat to said liquid to increase the volume thereof, the volume of liquid in relation to the electrodes being such that when the container is in its off position the path through the liquid to the electrodes is closed by hot liquid and is open after the temperature of the liquid returns to normal, said switch including a conductor connecting said heater in series with said indicator.

2. In a time delay electric switch for an electric circuit having a current responsive indicator therein, a container movable between on and off positions, a pair of spaced electrodes extending within the container, a body of thermally expansible liquid confined within the container and of a hot volume which closes the space between the electrodes for current flow and a cold volume which

breaks the current flow path when the container is in off position but maintains the current flow path with the container in on position, and an electrical heater in series with said flow path and located adjacent the container on position for applying heat to the liquid and spaced from the container off position to enable a liquid temperature drop, said switch including a conductor connecting said heater in series with said indicator.

3. In a delayed action switch for an electric circuit having a current responsive indicator therein, a heater, a container pivotally mounted for movement between an off position and an on position adjacent the heater for increasing container temperature, a pair of electrodes mounted in spaced apart relation within the container, and a body of thermally expansible liquid confined by the container and having a hot volume to close the space between the electrodes for completing a path of current flow between the electrodes and a cold volume which breaks said current flow path, said switch including a conductor connecting said heater in series with said indicator.

4. In a delayed action switch for an electric circuit having a current responsive indicator therein, a container enclosing a pair of spaced electrodes and a body of thermally expansible liquid, means pivotally mounting the container for movement between relatively upright and tilted positions related to the volume of liquid so that the liquid level submerges both electrodes in the container tilted position and breaks the current flow path between the electrodes in the upright position with the liquid at normal temperature but closes the current flow path with the liquid at an elevated temperature, and an electric heater in series circuit with the electrodes and positioned adjacent the container tilted position for elevating liquid temperature, said switch including a conductor connecting said heater in series with said indicator.

5. The structure of claim 4 wherein the position of the container is variable between said relatively tilted and upright positions to modify the intensity of heat application from the heater in controlling the rate of temperature drop and thereby the interval of cutoff delay following container movement away from fully tilted position.
